(57) CLAIM

The ornamental design for a golf club stand, as shown and described.

DESCRIPTION

FIG. 1 is a front perspective view of a golf club stand; FIG. 2 is an enlarged left side view of the top portion thereof;

FIG. 3 is an enlarged right side view of the top portion thereof;

FIG. 4 is an enlarged front elevation view the top portion thereof;

FIG. 5 is an enlarged rear elevation view the top portion thereof;

FIG. 6 is an enlarged top plan view thereof;

FIG. 7 is an enlarged bottom plan view thereof; and,

FIG. 8 is a front perspective side view thereof in an environment of use.

The broken lines show portions of the golf club stand that form no part of the claimed design. The wavy broken lines in FIGS. 2-5 show the bounds of the enlarged views and form no part of the claimed design. The dash dot broken lines in FIG. 8 show environment and form no part of the claimed design.

1 Claim, 6 Drawing Sheets
